DESIGN FOR A STOOL

Walter S. Gass, Seward, Nebr.

Application June 5, 1944, Serial No. 113,855

Term of patent 14 years

(Cl. D15—8)

To all whom it may concern:

Be it known that I, Walter S. Gass, a citizen of the United States, residing at Seward, in the county of Seward and State of Nebraska, have invented a new, original, and ornamental Design for a Stool, of which the following is a specification, reference being made to the accompanying drawing, forming a part thereof.

In the drawing: the single figure is a perspective view of a stool showing my new design.

I claim:

The ornamental design for a stool, substantially as shown.

WALTER S. GASS.
